SAMUEL J. BRANSON, OF CHICAGO, ILLINOIS.

BUILDING FALSE WORK.

1,323,823.

Specification of Letters Patent.

Patented Dec. 2, 1919.

Application filed June 26, 1919. Serial No. 306,840.

To all whom it may concern:

Be it known that I, SAMUEL JOSEPH BRANSON, a citizen of the United States, residing at Chicago, in the county of Cook and State 5 of Illinois, have invented certain new and useful Improvements in Building False Work, of which the following is a specification.

My invention relates to building false-work, which is used as a matrix to shape the concrete of girders, beams, and floor-slabs in modern reinforced-concrete-floored buildings.

Among its principal objects are efficacy, 5 economy and simplicity; efficacy in forming when erected a strong, firmly-joined, continuous matrix; economy, in imposing but a low requirement for labor—both in number of men and in point of time—for proper 10 erection and wrecking, and also in minimizing equipment necessary for speedy completion of a given job; and simplicity, both in the individual pieces and the manner of their interfitting, to make initial cost low and to 15 require only ordinary labor for the handling of the construction.

For the attainment of these objects, and others which will become apparent hereinafter, my invention consists in the combinations and the features of construction herein-after set forth, and to be claimed; reference being had to the accompanying drawings, 20 wherein—

Figure 1 shows, in perspective, the false-work in use;

Fig. 2 is a detail of a joist-box-cover;

Fig. 3 is a detail of a joist-box side-piece;

Fig. 4 is a longitudinal section from beam-to-beam;

Fig. 5 is a cross-section; and

Fig. 6 is a cross-section showing "wrecking" in progress.

It will be understood, preliminarily, that in building reinforced, poured-concrete floors, it is usual to provide deep beams or girders running one way (say cross-wise, for uniformity of relative directions as herein expressed) these being connected by shallower joists at right angles thereto and the 25 supporting grid thus formed being closed by floor-slabs; all of these portions merging integrally and making a common floor-level.

The false-work-matrix is usually of wood, (as is shown in the drawings) but metal 30 may be used in lieu thereof in many parts. It is erected to receive the concrete and rein-

forcing means which are duly placed; is left in place, in whole or in part, until the concrete is sufficiently set for stability; and then is knocked down and reerected for some 35 other floor. In this regard, a falsework construction which will permit certain strain-taking parts to be left in place, after the rest is wrecked, is important in order to insure the proper setting of the concrete and 40 yet to enable the building of successive floors to go forward rapidly with minimum equipment.

In the construction shown I provide, in 45 general, what I will term girder-mold forms; joist-soffit forms and box forms; these 50 co-operating so that the box-forms, which underlie the floor slabs may be wrecked, after the concrete is poured, without displacing or disturbing the girder-mold and joist-soffit 55 forms, which constitute a supporting grid for the interlocking elements of the box-forms.

In the drawings G are girders; J are joists 60 and S are floor slabs, all of concrete.

Each girder form, 10, consists of a trough, 65 made in sections of suitable length with bottom 11 and side boards 12, the whole supported on suitable pallets 13 and posts 14. The sides, 12, have spaced edge-notches 15 70 at their tops, as one convenient way of receiving and holding the bottom-shaping portions of the joist-molds. These notches are preferably formed as gaps between short strips 16 secured along the side-board edges 75 and in such notches there rest the ends of the flat bars 17 constituting joist-soffit forms each extending from one girder form to the next. Each of these joist-soffit forms is 80 strongly braced against vertical bending by 85 a deep vertical web 18, making of the form a vertical wooden T-beam. The ends of the web 18 are inclined, as at 19, for clearance to facilitate wrecking, and near its ends, in order to assist in carrying the load, the web 100 18 finds support on rails 20 running along the girder mold sides and spaced therefrom by the vertical battens 20'.

The girder-forms 10 and joist-soffit forms, 17 it will be noted, constitute, a grid, supported on the posts 14, this grid being independent of the box-forms and adapted to remain in place to sustain the soffits of the girders and joists after the box-forms have been wrecked. When the box-forms are in 110 place the grid takes the load so that the box-forms may be of rather light construc-

tion as is advantageous to facilitate handling.

Each joist-soffit form, 17, has on its web 18 shoulder-blocks 21, and on these there 5 rest, loosely, supporting cross-boards 22. These parts afford in convenient fashion a readily-removable box-form support for each grid-space, on which supports the proper box-form 23, may be set up. Each 10 box-form comprises separable side, end, and top members, respectively numbered 25, 26 and 27 all carried by the grid aforesaid. Sides 25 (Fig. 3) have vertical cleats or battens 28, some of which carry beveled blocks, 15 29, intended to interlock with the top, this being an advantageous way of spacing the blocks 29 away from the sides in connection with desirable bracing of said sides against warping. Similarly these cleats act as 20 spacers on which rails 30 are mounted near the bottom edges of the side-boards so that such rails may rest firmly on the cross-supports 22, which the side-board faces make contact with the sides of the joist-soffit forms 25 17 and then selves define the side faces of the joist-molding spaces. Spreaders 31, loosely laid across from rail to rail, and preferably abutting against the battens 28, keep the 30 side-boards from bulging away from the joist-soffit forms when the concrete is poured. These side-boards I arrange so that they help to position the ends and tops of the box-mold, and I make them removable, in wrecking, before the top and ends are taken 35 down.

The extremities of each side-board slope inwardly as shown, and the box-end members 26 lap over the side-board ends and rest in inclined position against them, preferably 40 with the lower edges of said box-ends resting on the girder-mold side-strips 16. Battens or cleats 32, running vertically, in spaced relation up the end-members, protrude as studs 32' at their lower ends below 45 the lower edge of the end-board, and rest against the outside of the girder-side-board. Also they straddle a block or lug 33 on the girder-side-board. In this way, as a simple and desirable specific detail, the end-boards 50 of the box-forms are positioned against end-wise slipping and against moving out of contact with the side-boards 25. And to aid in positioning the top board 27, the end-cleats 32 have a strap 34 secured across them 55 at their upper ends, to complete a socket for a top-tongue.

It will be noted that, as illustrated in Fig. 6, the side boards 25 are free for removal in advance of the end-boards 26 without 60 disturbing the position of the latter, which define the upper portions of the girder-sides between the joists, and which, by virtue of their inclination, give the girders G a desirable breadth and strength at their tops.

Each top board 27, bearing marginally

upon the edges of the side-boards and end-boards has suitable reinforcing cross-cleats 36 and is provided with lengthwise tongue-strips 37, and cross-wise tongue-blocks, 38, arranged to interlock with the appropriate 70 parts of side and end boards, viz: the end tongues 38 of the top entering the sockets of the box-ends and held by parts 32, 34; and the lengthwise tongues 37 of the top entering between blocks 29 and the side-boards. In a sense, the top fits on the sides and ends like an inside-flanged cover but also it prevents the ends and sides from being outwardly displaced at their upper 75 edges, as would an outside flanged cover. 80

In erection, the grid of girder-forms and joint-soffit forms is first placed on supporting posts and pallets and then conveniently the loose parts are placed in this order: supports 22, sides 25, ends 26, spreaders 31 and 85 top 27. It will be observed that all box-form parts are merely placed in interlocking relation without any necessity for nailing or other joinder, and that in their interlocked positions all parts of the box-structure are very strongly and solidly maintained against accidental displacement; the cross-supports 22 and spreaders 31, however, being easily demountable key-pieces which are not locked in position but are not 90 apt to be accidentally displaced. 95

For wrecking, after the concrete has been poured or spread, the falsework is accessible, of course, only from below. One removes the spreaders 31, knocks the supports 100 22 off the shoulder-blocks 21 and swings in and lowers the side-boards 25 as shown in Fig. 6. This frees the end-boards, which are then pried inwardly, unseating from the girder-mold-strips 16 as the cleats 32 escape 105 beyond blocks 33. This frees the top, which is then readily taken down, if, indeed, it has not come down with the end boards. These parts being all rather light, they may be handled with greatest ease. The result of 110 such partial wrecking is to leave the grid of girder-forms and joist soffit forms intact. This is of great advantage for the following reason among others:

In the erection of buildings I have found 115 it entirely feasible to remove the box-forms about 24 hours after pouring of the concrete because the rather thin floor-slab portions carry little load and set readily; but for best assurance of a proper setting of the 120 thicker, strain-carrying joists and girders it is very desirable to maintain their false-work support for a number of days. By my present construction, therefore, I am able to use one set of the box-mold parts in connection with two or more sets of the grid-mold parts, making one box-form equipment serve 125 an entire building erected at say a floor-a-week rate.

Taking down the grid, as will be appar- 130

ent, is very simple, since removal of the parts or shoring 14, for any girder frees that girder form and the contiguous joist soffit-forms for lowering and withdrawal, 5 each joist-form, 17, disengaging readily from its end supporting girder forms.

It will be understood that in wood construction falsework, as herein shown, permanently connected parts, such as the cleats, 10 rails, blocks, etc., are nailed or screwed to their respective carriers.

While I have herein described in some detail a specific embodiment of my invention in a form which I have found to be practical and satisfactory, I do not limit my invention in its broader aspects to details as shown, for many changes in construction may be made within the spirit of my invention and within the scope of the appended 20 ed claims.

What I claim is:

1. Building falsework comprising girder-mold members and joist-soffit mold members arranged for assembly to constitute a supporting grid, and box-mold side and top members adapted for assembly in interlocked relation to constitute closures for the grid-openings and arranged for individual removal through said openings, in wrecking, without disturbing the grid. 30

2. Building falsework comprising girder-mold members and means to position them; joist-soffit form members separably mounted on said girder-mold members, each to shape 35 the soffit of a concrete joist and to support it in setting; and box-mold members comprising separable sides, ends and top, detachably mounted on the grid formed by said girder-form and joist-form members and removable said separable members individually from below through the grid openings. 40

3. Building falsework comprising, in combination, girder forms, joist-soffit forms extending therebetween in spaced relation 45 each comprising a flat topped strip and a vertical web, supports spanning between and carried by said webs, and box-forms comprising interlocked top, end and side members, said side members bearing on said cross-supports. 50

4. Building falsework comprising spaced girder-troughs, T-beam joist-soffit forms resting on said troughs and spanning from one to another thereof to form a grid and box-forms each composed of side, end and top members, which said members are removable through the opening between the girder troughs and T-beams, said side and end members supported by the beams and 55 girder troughs and said top interlocking with and overlying both the sides and ends. 60

5. Building falsework comprising girder-forms, joist-soffit forms supported by said girder forms and constituting therewith a grid and box forms comprising side mem- 65

bers supported on the joist-soffit forms, end members supported on the girder forms and top members interlocking with the side and end members.

6. Builders' falsework comprising in combination girder-forms, parallel and spaced apart; joist-soffit forms at right angles thereto and bearing thereon to form a grid, supports loosely bearing on and supported by said joist-soffit forms for removal from below, and box-forms mounted on said supports and comprising side, end and top members interlocking at their tops and individually removable through the grid opening after removal of said supports. 70

7. Builders' falsework comprising, in combination, structure forming a grid, blocks fixed to opposite members of said grid, supports loosely laid on said blocks, spanning between said opposite grid-members and laterally removable therefrom, side box-members bearing on said supports, and end and top box-members co-operating with said side members, said end, side and top members interlocking for self-maintenance 80 in erection position but for individual removal through the grid after removal of said supports. 85

8. Building falsework comprising, in combination, girder forms having notched upper edges, joist soffit forms resting in said edge-notches and having supporting blocks, cross supports resting on said blocks, and box-forms each comprising sides carried by said cross supports, ends abutting thereagainst and a top interlocking with the sides and ends. 100

9. Building falsework comprising, in combination, girder forms, joist soffit forms carried thereby and having supporting blocks; cross supports resting on said blocks and laterally removable therefrom, and box forms each comprising end members resting on, locking with but inwardly removable from the girder forms, side boards between the ends resting on the cross supports but removable inwardly when the latter have been displaced, and a top member interlocking with the side and end boards but permitting their stated removals. 105

10. In a concrete falsework, a box-form comprising side boards, end boards lapping the end edges of the side-boards, and a top board interlocking with the upper portions of the end and side boards and overlying their edges. 110

11. In a concrete falsework, a box-form comprising side boards, end boards lapping the end edges thereof, and a top board overlying the upper edges of the end and side 115 boards, and interlocking means between the top board and the upper portions of the end and side boards retaining the said upper portions against outward or inward displacement by rocking of the end or side 120 125

- boards on their bottom edges, but permitting rocking of the said boards on their upper, interlocked edges and downward withdrawal of said boards to break the interlock. 5
12. In concrete falsework, a box form comprising side boards and end boards closing the box-perimeter and a top board, said boards detachably interengaged to prevent 10 collapsing by lateral inward movement of the upper portion of any perimetral board and to permit detachment of the boards upon inward displacement of the lower portion of one of said perimetral boards. 15
13. In concrete falsework a box-form comprising perimetral boards including side boards and end boards, and a top board, said boards, detachably inter-engaged adjacent the top to prevent collapsing of the box by 20 any lateral displacement of the upper portion of any perimetral board or the top-board and to permit downward removal of said boards upon the inward displacement of the lower end of a perimetral board; and 25 detachable means for preventing inward displacement of any perimetral board.
14. In concrete falsework, a box form comprising side boards, end boards and a top board, said side boards and end board 30 and top board being detachable from each other and said top board having interlocking connection with said side boards and also with said end boards endwise of the end boards, whereby movement of said side 35 boards in a direction endwise of said end boards is restrained.
15. In concrete falsework, a box form comprising side boards, end boards, a top board, said side boards and end boards and top board being detachable from each other and said top board being arranged 40 to interlock with said side and end boards, and removable spreaders extending between and abutting against said side boards, said side boards and end boards and top 45 board being collapsible inwardly when said spreaders are removed.
16. In concrete false work, a collapsible box form comprising side members and end members and a top member, such members 50 being arranged to be interlocked and keyed together in erected position, for self-maintenance in such position and for ready individual withdrawal downwardly, whereby said box-form is non-collapsible under pressure from without and may be wrecked from within. 55
17. In concrete falsework the combination of a collapsible box-form comprising perimetral members, including sides and ends, and a top member, such members having provision for interlocking detachably for self maintenance in erected position so long as the bottom edges of the perimetral members are not displaced, and for ready 60 separation from within upon displacement of the bottom edge of one of said perimetral members, means to support said box form and readily detachable means for preventing displacement of the bottom-edge of any 65 said perimetral member. 70

SAMUEL J. BRANSON.
